DISPOSABLE LIQUID FILTER CARTRIDGE

Vernon D. Roosa, ½ Standadyne Inc., P.O. Box 1440,
West Hartford, Conn. 06101

Filed June 15, 1970, Ser. No. 23,490

Term of patent 14 years

Int. Cl. D23—01

U.S. Cl. D23—4

FIG. 1

FIG. 2

FIG. 3

FIG. 5

FIG. 4

FIG. 6

FIG. 7

FIG. 8

FIG. 9

FIG. 1 is a front elevation of a disposable liquid filter cartridge showing my new design;

FIG. 2 is a rear elevation thereof;

FIG. 3 is a top plan view thereof;

FIG. 4 is a bottom plan view thereof;

FIG. 5 is an elevation taken from the left side thereof;

FIG. 6 is a perspective view of a modified form of the disposable liquid filter cartridge shown in FIG. 1, where the modification resides in an opaque cover;

FIG. 7 is a rear elevation of FIG. 6;

FIG. 8 is an elevation taken from the left side of FIG. 6; and

FIG. 9 is a bottom plan view of FIG. 6.

FIGS. 1 and 5 are shaded to show contrast of color.

The color black is shown in FIGS. 1 and 5 but coloring is not essential except for contrast.

I claim:

The ornamental design of a disposable liquid filter cartridge, as shown and described.
